VACUUM CLEANING MEANS FOR THREAD- WORKING TEXTILE MACHINES

Jacob H. Norman, Gastonia, N.C.

Filed Aug. 9, 1963, Ser. No. 301,089

6 Claims. (Cl. 19—245)

This invention relates to the general field of thread-working textile machines, and more specifically, the invention pertains to the provision of means for preventing the accumulation of dust, lint, and other debris in spinning machines which could ultimately lead to the formation of a slug.

In accordance with the teachings of this invention, one of the primary objects is to provide vacuum or suction means to remove dust, lint and other foreign materials from a textile spinning frame or related machine.

A further object of this invention is to provide vacuum or suction means for the rollers of a textile spinning frame as well as vacuum or suction means for removing dust, lint and other foreign substances from the top and bottom aprons and from their associated cradles.

Still another object of this invention is to provide vacuum or suction-operated means for picking up dust, lint, and other similar materials from a spinning frame in order to reduce the probabilities of electrostatic explosions.

This invention contemplates, as a still further object thereof, the provision of means of the type generally referred to supra, the means being non-complex in construction and assembly, inexpensive to manufacture, and which is durable in use.

Other and further objects and advantages of the instant invention will become more evident from a consideration of the following specification when read in conjunction with the annexed drawings, in which:

FIGURE 1 is a perspective view of a conventional stand of a spinning frame, FIGURE 1 illustrating the adaptation of the vacuum or suction means constructed in accordance with this invention thereto;

FIGURE 2 is a perspective view of the vacuum or suction means, per se, in accordance with this invention;

FIGURE 3 is an enlarged, detail, cross-sectional view of the spinning frame, FIGURE 3 being taken substantially on the vertical plane of line 3—3 of FIGURE 1, looking in the direction of the arrows;

FIGURE 4 is a fragmentary, detail, perspective view illustrating the application of the vacuum or suction means as applied to the cradle;

FIGURE 5 is a detail, fragmentary, cross-sectional view, FIGURE 5 being taken substantially on the inclined plane of line 5—5 of FIGURE 3, looking in the direction of the arrows; and

FIGURE 6 is a fragmentary bottom plan view of the spinning frame, FIGURE 6 being taken substantially on the horizontal plane of line 6—6 of FIGURE 5, looking in the direction of the arrows.

Referring now more specifically to the drawings, reference numeral 10 designates, in general, a single stand, it being understood that a plurality of stands may be connected therewith on either side thereof in accordance with the accommodations which are available. The spinning frame stand 10 includes an elongated, substantially rectangular, horizontal support 12 hereinafter referred to as a base support, the base support 12 having fixedly connected thereto a plurality of upwardly-projecting standards 14. Each of the standards 14 has rigidly affixed thereto an elongated, substantially rectangular leg portion 16 of a support bracket 18. It will be noted that the leg portion 16 is inclined upwardly and away from the base support 12 at an acute angle relative thereto. The

2

bracket 18 includes a bifurcated foot portion 20 which projects substantially at right angles relative to the leg portion 16 and includes the arms 22, 24. An elongated, substantially rectangular support bar 26 is rigidly secured to each of the leg portions 16 intermediate the ends thereof, the support bars 26 projecting longitudinally beyond each of its associated leg portions 16 of the support bracket 18. Each of the support bars 26 is provided with downwardly-opening recesses 28, 30, the recesses 28, 28 and 30, 30 being aligned one with the other. The outer ends of each of the support bars 26 are also provided with transversely-extending, downwardly-opening recesses 32 which are disposed in confronting aligned position.

Reference numerals 34, 36 and 38 designate front, middle and back bottom rolls, respectively, of conventional construction and which include the axially-fluted portions 40, 42 on the front and back rolls 34, 38, and the knurled portions 44 on the middle roll 36. Each of the rolls 34, 36 and 38, intermediate their respective fluted or knurled portions, is formed with smooth cylindrical sections 46, 48, 50 of reduced diameter. The opposed ends of the rolls 34, 36, 38 are further reduced in diameter as at 52, 54, 56 to be journaled for rotation between the arms 22, 24 and in the recesses 28, 30. The opposed ends of an elongated back bar rod 58 are journaled for rotation within the recesses 32.

The back bar rod 58 has fixedly secured thereto adjacent the opposed ends thereof one end of a pair of right and left-hand end arms 60 (only the right-hand arm being shown in FIGURE 1) of conventional construction. Also, a plurality of intermediate arms 62 have one of their respective ends fixedly connected with the back bar rod 58. The end and intermediate arms 60, 62, adjacent their respective outer ends, are connected to one of the ends of elongated rods 64 having blocks 66 fixedly connected to the other ends of the rods, all in the conventional manner. The adjacent sides of the end and intermediate arms 60, 62 as well as their associated blocks 66 are formed with a plurality of grooves 68 (see FIGURE 6) which receive therein the opposed reduced ends 70, 72, 74 of pairs of front, middle and back upper rollers 76, 78 and 80, respectively.

Each of the rolls 76, 78, 80 is coaxially-aligned with one another and extend parallel to the coaxially-aligned rolls 40, 44 and 42, in that order. The roll 76 overlies the roll 40, the roll 78 overlies the roll 44, and the roll 80 overlies the roll 42. All of this structure is conventional and well-known in the art.

Also, in the conventional manner, each roll 76, 78, 80 has an intermediate axially-extending smooth portion of reduced diameter, as is indicated at 82, 84, 86, which confronts the smooth portions 46, 48, 50 of the bottom rolls 40, 42, 44. The rolls 76, 80 rest on the rolls 40, 42 under the force of gravity, and the rolls 78 are supported in cradles generally indicated at 88. Each cradle 88 includes a pair of side frame members 90, 92 having a generally rectangular configuration, the side members 90, 92 being held in spaced and substantially parallel relation by a spacer chuck 94 and an L-shaped back bracket 96. The front ends of the side frame members 90, 92 are spanned by the conventional U-shaped clamps 98 (see FIGURE 4), having arms 100, 102 which engage within notches 104, 106 formed in the side frame members 90, 92, all in the conventional manner.

The middle roll 44 is received within notches 108, 110 formed in the side frame members 90, 92 and the side frame members 90, 92 are also provided with upwardly-opening notches 112, 114 to receive therein reduced portions of the upper middle roll 78.

The roll 44 and the arm 102 have an endless apron 116

trained thereabout, and the arm 100 and the roll 78 have a similar apron 118 of continuous length also trained thereabout. It will be understood from the drawings that the two aprons have confronting and contracting adjacent surfaces. This is all conventional structure.

Extending between and supported on the standards 14 of each stand 10 is an ovate tube 120 having openings 122 formed in the smaller end thereof, the openings 122 being disposed below the rolls 40. Each tube 120 connects through a pipe 124 with a vacuum or suction source (not shown). Each of the ovate tubes 120 has a plurality of substantially hollow tubular T-connectors fixedly secured therewith, the connectors being designated by reference numeral 126, and a connector 126 is provided for adjacent pairs of cradles 88. Each connector includes a stem 128 in open communication at one end thereof with the tube 120, and being in open communication with a crosshead 130 which opens through the opposed side walls 90, 92 of the immediately adjacent pairs of cradles 88 through confronting openings 132, 134 (see FIGURE 6). The crossheads 130 extend above and below the contacting portions of the aprons 116, 118 whereby dust, lint or other foreign substances may be drawn from the interior of each apron.

Also fixedly connected with the back bar rod 58 are the arcuate ends 136, 138 of a plurality of clamps 140 having a pair of substantially rectangular portions 142, 144 which are secured together by means of a screw 146 and nut 148. The other ends of the central portions 142, 144 also terminate in arcuate ends 150, 152 which clampingly embrace an elongated, hollow, substantially cylindrical tube 154 having a plurality of substantially rectangular inlet bosses 156 projecting therefrom and to which are connected one of the ends, respectively, of a plurality of elongated, substantially hollow, rectangular picker tubes 158 having downwardly-facing, transversely-extending openings 160. The picker tubes 158 overlie the end arms 60 and the intermediate arms 62, with the openings 160 overlying the reduced journaled ends 70, 72, 74 and the reduced intermediate portions 82, 84 and 86 of the upper rolls 76, 78 and 80. These features of the invention are clearly shown in FIGURES 1, 3, 5 and 6.

Referring now more specifically to FIGURE 2 of the drawings, it will be seen that the hollow cylindrical tubular member 154 connects through a C-shaped connector 168 in a slip-fit, and the other end of the connector 168 connects through a slip-fit with one end of an elongated, hollow, substantially cylindrical connector tube 170. The other end of the connector tube 170 is also provided with a slip-fit within the hollow, cylindrical boss 172 which opens into the pipe 124. From the foregoing it will be seen that as suction is supplied to the tube 120, vacuum or suction is applied to the picker tubes 158, whereby all lint, dust, and other foreign substances which have a tendency to accumulate on the reduced diameter portions of the upper rolls will be picked up and led to a suitable point of discharge. It is desirable to employ clamps of the type illustrated at 140 whereby the tubular member 154 may be rotated about its longitudinal axis, thereby raising the picker tubes 158 from their full-line position shown in FIGURE 3 to their dotted-line position therein. The use of this type of clamp also permits the end and intermediate arms to be rotated with the back bar rod 58 in the event it is necessary to inspect or make changes in the front, back or intermediate lower rolls.

The openings 122 formed in the tube 120 serve to draw the broken or severed ends of rovings 200 which are, of course, threaded between the pairs of rollers 42, 80 and between the aprons 116 and 118 from which the rovings pass between the rolls 40, 75.

While the above-described invention has been described and illustrated in the environment of a spinning frame, it will be understood that this invention may be extended for inclusion with any textile manufacturing equipment which may employ rolls.

Having thus described and illustrated one embodiment of this invention in detail, it will be understood that the same is offered merely by way of example, and that the instant invention is to be limited only by the scope of the appended claims.

5 What is claimed is:

1. Vacuum cleaning means for a thread-working textile machine comprising a stand having front, middle and back bottom rolls, front, middle and back upper rolls extending parallel to and overlying said front, middle and back bottom rolls, a cradle supported on the middle roll of said bottom rolls and rotatably supporting said upper middle roll, said cradle having an opening formed therein, a substantially U-shaped clamp extending transversely of said cradle and including a pair of arms extending substantially parallel to the axes of said bottom and upper rolls, an apron trained over the middle roll of each of said bottom and upper rolls and one of said arms, each of the complementary aprons having portions contacting each other, vacuum means disposed below the front roll of said bottom rolls and opening toward the front of said stand, and a tubular connector connecting the opening of the cradle to the interior thereof opposite the interior of and adjacent the contacting portions of the aprons to said vacuum means to remove dust, lint and other foreign substances from the interiors of said aprons.
- 10 2. Vacuum cleaning means for a thread-working textile machine as defined in claim 1, wherein said rolls have reduced diameters at axially-spaced intervals, and vacuum means supported on said stand overlying said reduced diameter portions of said rolls to pick lint, dust and other foreign substances therefrom.
- 15 3. Vacuum cleaning means for a thread-working textile machine comprising a stand having front, middle and back bottom rolls, front, middle and back upper rolls extending parallel to and overlying said front, middle and back bottom rolls, a cradle supported on the middle roll of said bottom rolls and rotatably supporting said upper middle roll, said cradle having an opening formed therein, an apron trained over the middle roll of each of said bottom and upper rolls, each of the complementary aprons having portions contacting each other, vacuum means disposed below and extending along the front roll of said bottom rolls and opening toward the front of said stand, and other vacuum means connecting the opening of the cradle to the interior thereof opposite the interior of and adjacent the contacting portions of the aprons to said vacuum means to remove dust, lint and other foreign substances from the interiors of said aprons.
- 20 4. Vacuum cleaning means for thread-working textile machines comprising a stand having front, middle and back bottom rolls, said bottom rolls being disposed in spaced relation in a plane which is inclined with respect to said stand, front, middle and back upper rolls extending parallel to and overlying said front, middle and back bottom rolls, a cradle, having an opening formed therein, for said bottom and upper middle rolls, said cradle including a pair of sidewalls of substantially rectangular configuration disposed in laterally-spaced and substantially parallel relationship, said sidewalls rotatably receiving said bottom middle roll and rotatably supporting said upper middle roll, a substantially U-shaped clamp mounted on and carried by said sidewalls, said clamp including a pair of arms disposed in spaced parallel relation relative to one another and with respect to said bottom and upper middle rolls, an apron trained about each of said bottom and upper middle rolls and one, respectively, of said arms, said aprons being disposed for surface-to-surface contact over a portion of their length to receive rovings therethrough, and vacuum means disposed below and extending along the front roll of said bottom rolls and opening toward the front of said stand, another vacuum means connecting the opening of the cradle to the interior thereof opposite the interior of and adjacent the contacting portions of the

aprons to said vacuum means to remove dust, lint and other foreign substances from the interior of each of said aprons.

5. Vacuum cleaning means for thread-working textile machines as defined in claim 4, wherein said stand includes a plurality of end and intermediate arms rotatably supported thereon, said upper rolls being rotatably supported on said end and intermediate arms, said upper rolls being provided with reduced ends and intermediate portions, and further vacuum means superimposed over 10 said portions of said rolls having reduced ends.

6. Vacuum cleaning means for thread-working textile machines as defined in claim 5, and a back bar rod mounted for rotation on said support and having one of the ends of said end and intermediate arms fixedly secured thereto for rotation therewith, a plurality of clamps having one of their respective ends fixedly secured to said

back bar rod at axially-spaced intervals, a substantially hollow tubular member fixedly connected within said clamps, said further vacuum means embodying a plurality of picker tubes, said picker tubes being substantially hollow throughout their length and having one of their ends fixedly connected to said tubular member, the other ends of said picker tubes having openings extending transversely therethrough and superimposed over said reduced portions of said upper rolls, and means connecting said tubular member with said first-mentioned vacuum means.
